UNITED STATES PATENT OFFICE.

ELIHU THOMSON, OF NEW BRITAIN, CONNECTICUT.

DYNAMO-ELECTRIC MACHINE.

SPECIFICATION forming part of Letters Patent No. 294,094, dated February 26, 1884.

Application filed May 23, 1883. (No model.)

To all whom it may concern:

Be it known that I, ELIHU THOMSON, a citizen of the United States, and a resident of New Britain, in the county of Hartford and State of Connecticut, have invented certain new and useful Improvements in Dynamo-Electric Machines and Motors, of which the following is a specification.

My invention relates to the construction of dynamo-machines, magneto-electric machines, or electric motors; and its object is to provide a machine that shall be simple, cheap, compact, and efficient, and especially suitable for use in electroplating, although not limited to such use.

My invention consists in certain novel features of construction and improvements, that will be described with reference to the accompanying drawings, and will be specified in detail in the claims at the end of this specification.

In the accompanying drawings, Figure 1 is a perspective view of the machine, showing the general form thereof. Fig. 2 is a view from the commutator end. Fig. 3 is a vertical longitudinal section through the frame and the field-magnet, showing the armature in place. Fig. 4 is a transverse section on the line *x x* of Fig. 3. Fig. 5 is an outline view, illustrating the method of winding the armature. Fig. 6 shows the manner of connecting the armature-coils to one another and to the commutator. Figs. 7, 8, 9, and 10 show the various positions of the armature-coils in a revolution of the armature, and illustrates the manner in which currents are generated and taken off in the various positions. Fig. 11 is a perspective view of the commutator separated from the other parts. Fig. 12 is an edge view of an adjustable commutator for varying the overlap between successive segments. Fig. 13 shows a modified arrangement of commutators and brushes therefor. Fig. 14 shows a preferred arrangement of circuits when the machine is used with a plating or depositing bath, or with a secondary or storage battery or similar apparatus.

In Fig. 1, *P* is the driving-pulley upon the armature-shaft, and *K* the commutator at the opposite end of the shaft, said shaft being mounted in suitable bearings or standards in a frame, *D B*, of iron.

A indicates the armature of the machine, revolving between the curved pole-pieces *N S*. The said armature is wound with two coils at 55 right angles to one another in the manner to be presently described, and is shown in end view, Fig. 2, in place between the pole-pieces *N S*, curved to the outline of the armature.

C indicates the field-magnet coils, through 60 which a current is taken from the armature, and which are arranged either in direct circuit with the working-resistance, in derived circuit thereto, or in any other suitable manner, or may be supplied with currents from 65 some other source. The coils *C* are wound upon a central mass of iron, *D'*, suitably attached to or formed in one with the frame *D B*, and continued outward, as shown in Fig. 3, to form one of the pole-pieces, *N*. The other 70 pole-piece, *S*, is formed in or on the bed-plate of the machine. The core *D'* is perforated longitudinally and centrally for the armature-shaft, so that its axis and the armature-axis 75 practically coincide.

It will be seen that the base-plate *D B* forms practically a continuous mass with the core *D'* of the coil *C*, the pole-piece *N* carried thereby, and the pole *S*. This construction not only secures great compactness, but also produces 80 a strong magnetic field for the armature to revolve in. The commutator-brushes are applied and constructed or mounted in the usual or any suitable manner. The armature-carrier is constructed in any desired manner, and 85 the armature-coils are wound thereupon in the manner illustrated in Figs. 5 and 6. Two coils are employed on the armature, wound in the general direction shown in Fig. 5, and preferably at right angles to one another, al- 90 though this angle may under suitable modifications of the commutator be changed. The two coils cross each other near the armature-shaft, and two of the ends of said coil are united, as at *J*, Fig. 5, while the two other or 95 free ends of said coils are shown at *e* and *f*. One lap or convolution only of each coil is shown for the sake of simplicity. The compound end *J* is connected, as shown in Fig. 6, to one of the segments, *K¹*, of a three-segment 100 commutator. The opposite or single ends of the two coils are connected one to a segment, *K²*, and the other to a segment, *K³*, as clearly indicated in Fig. 6.

A A² indicate the two coils at right angles to one another, and the connections are made in the order shown. Currents are generated in the coils themselves in the usual way, as 5 the armature revolves between the curved pole-pieces N S.

The manner in which the currents are collected and commutated is shown in Figs. 7, 8, 9, and 10. In Fig. 7 the brushes bear on segments K² K⁴ only, and the current is taken from one coil only, since the free or single end of the other coil is connected to segment K³. The small arrows indicate the direction of flow of current. The large arrow W indicates the direction of revolution of the armature. In Fig. 8 the upper brush bears upon both segments K² K³, while the lower brush bears upon the segment K⁴. The current is then taken from both coils in multiple arc, as 20 indicated. The conditions in Figs. 9 and 10 will be readily understood from the drawings, the arrows indicating the direction of flow of the currents. In all cases it will be seen that the terminals that are negative and positive 25 respectively are connected at the proper moment with the positive and negative commutator-brushes, and that a continuous current is thereby obtained.

It is advisable to have the slots between 30 segments made so that the segments will overlap and allow a prolonged contact of the brushes and segments at the time of change from one segment to another. Such a construction is shown in Fig. 11, where the slots between segments K² K³, to which the ends e f are respectively connected, is shown as sufficient to give an overlap, say, of forty degrees, while the overlap between each of said segments and the segment K⁴, to which the compound end 35 of the coils is connected, is sufficient to give an overlap of twenty to twenty-five degrees. It should be remarked that the extent of overlap between the singly-connected segments K² K³ should be in any case much greater than 40 that between them and the doubly-connected segment K⁴. The exact amounts of overlap to give the highest efficiency of operation in any case cannot be stated precisely, since it varies with every change in the magnetic and electrical relation of the field-magnet and armature 45 of the machine. These relations admit of wide variance. In general, however, it may be stated that the higher the field or the greater its strength relatively to the magnetic and electrical strength of the armature the less should 50 be the overlap. In working with a low field the commutator-overlap should be great. The amount of overlap may be made adjustable by constructing the commutator in two parts, 55 mounted upon separate supports adjustable with respect to one another. Such a construction is indicated in Fig. 12, where L M indicate two slotted rings or sections, each composed of three insulated segments insulated 60 from the shaft and from each other by suitable means. Each pair of segments in the two rings that are in approximately the same cir-

cumferential position are electrically united to one another or to the same coil end, so as to form electrically a single segment. The rings 70 are fixed in the desired position with relation to one another by set-screws R, passing through hubs I, upon which said rings are mounted. It is very easy to so adjust the overlap by this means as to obtain the best action of the apparatus. 75

Instead of making all the segments overlap, the same end may be accomplished by the arrangement shown in Fig. 13, in which straight slots are made between the segment K⁴ and 80 its adjoining segments K² K³, and an irregular slot is made between K² and K³, the latter slot being arranged to give an overlap, say, of twenty to twenty-five degrees. The latter overlap is practically extended to the proper 85 length by the employment of double commutator-brushes W², the two portions of which are placed, say, twenty degrees apart. This also gives the required overlap between or at the dividing-points between the segment K⁴ 90 and segments K² K³.

In cases where the machine is used for electroplating or electro-deposition, or for charging secondary or storage batteries, or in other connections where a counter or return current 95 from the work may endanger the polarity of the field-coil, I prefer to use the arrangement of circuit shown in Fig. 14, where K is the commutator connected, as before described, to the armature-coils, and C is the field coil or 100 coils of the machine.

R² is the plating or depositing bath or other apparatus; and G is a secondary battery connected around the field-coil C, and whose counter electro-motive force is sufficient to force all 105 the generated current through the coil C, no current during normal operation passing through said battery G when charged. In ordinary cases a single pair of elements in G will suffice for this end on account of the very low resistance, which in a plating-machine is given to the field C. The object of this introduction of the battery G is to prevent a reversal of the field-magnets by an inverse current from the bath R² on the stoppage or slowing of the armature of the machine. When such stoppage 110 takes place, the reactionary current from the bath R² simply passes, as shown by the arrow, through the secondary cell G without interfering with the field-coil C. In fact, if the surface exposed by the plates of the cell G be sufficiently great, a current will be sent by it 115 through the field-coil C in the proper direction to maintain its magnetism, even after stoppage of the machine. 120

These advantages are secured without any loss of the reactionary effect of the field itself, and differ in this respect from existing devices to secure the same end. 125

I make no claim herein to the arrangement 130 shown in Fig. 14 for preventing reversal of the field-magnet, but shall make the same the subject of a separate application for patent.

What I claim as my invention is—

1. The combination, in a dynamo-electric machine or motor, of a field-magnet core, through which and parallel with whose axis the armature-axis passes, and two or more 5 pole-pieces, between which the armature rotates, said pole-pieces being magnetically connected with the opposite ends of the core, so as to be of opposite polarity.
2. The combination, in a dynamo-electric 10 machine or motor, of a field-magnet having a longitudinally perforated core, an armature whose axis passes through the core, and pole-extensions projected from opposite ends of the core, and respectively of north and south 15 polarity, said pole-extensions forming the magnetic pole-pieces between which the armature rotates.
3. A field-magnet for a dynamo-machine, the axis of whose core coincides with the 20 armature-axis, and provided with field-of-force poles formed the one by a direct extension from said core and the other by the base-plate to which or with which said core is in magnetic connection.
- 25 4. The combination of the frame D B of iron, core D', formed with or secured thereto, pole-pieces N S, coils C, and an armature, A, mounted on a shaft passing through the core D'.
5. In a dynamo-electric machine or motor, 30 an armature wound with two coils or conducting wires in different planes or positions, two of the four terminals of said coils being united together and to a commutator-segment, while the other terminals are singly connected to 35 two other commutator-segments, substantially as set forth.
6. In a dynamo or magneto electric machine or motor, a system of two revolving coils wound in different planes or positions, 40 as described, united by a joint formed of two of the terminals at a commutator-segment,
- and having their other or remaining terminals connected to the two other segments of a three-segment commutator.
7. The combination, substantially as de- 45 scribed, of two armature-coils and a three-segment commutator, one segment of which is united to a terminal from each coil, while the remaining segments are separately connected to the remaining terminals of said coils. 50
8. The combination, with a set of two armature-coils or armature-helices, of a three-segment commutator, the overlap of whose segments is made unequal, as described.
9. The combination, with a set of two armature-helices, of a three-segment commutator, 55 connected, as described, to said helices, and having an overlap between its successive segments approximately twice as long at one of its points between the segments connected to 60 single ends of the armature-helices as is the overlap at the two other points.
10. In a magneto or dynamo electric machine or motor, a commutator-cylinder made in two sections adjustable with respect to one 65 another, as described, so as to permit the overlap between successive commutator segments or sections to be adjusted.
11. A commutator for a dynamo-electric 70 machine or motor, consisting of two commutator-rings, L M, each divided into the proper number of segments, and means for setting the divisions of said ring at any desired circumferential angle with relation to one another.

Signed at New Britain, in the county of Hartford and State of Connecticut, this 21st day of May, A. D. 1883.

ELIHU THOMSON.
